Filed July 24, 1959, Ser. No. 56,910

Term of patent 14 years

(Cl. D16—3)

FIG. 1

FIG. 2

FIG. 3

FIG. 1 is a top plan view of a tablet showing my new design.

FIG. 2 is a front elevational view thereof.

FIG. 3 is a rear elevational view.

The characteristic features of my design reside in the generally trapezoidal shape of the tablet in plan, the symmetrical convex top and the bottom faces and the symmetrical tapering of all the edges, all as shown.

I claim:

The ornamental design for a tablet, substantially as shown and described.
